UNITED STATES PATENT OFFICE.

EDGAR W. CLEVELAND, OF HOLLAND, MICHIGAN.

JOURNAL ADJUSTMENT FOR ARMS OF MULTIPLE-SPINDLE DRILLS.

1,350,004.

Specification of Letters Patent. Patented Aug. 17, 1920.

Application filed September 29, 1919. Serial No. 327,105.

To all whom it may concern:

Be it known that I, EDGAR W. CLEVELAND, a citizen of the United States of America, residing at Holland, in the county of 5 Ottawa and State of Michigan, have invented certain new and useful Improvements in Journal Adjustments for Arms of Multiple-Spindle Drills; and I do hereby declare the following to be a full, clear, and 10 exact description of the invention, such as will enable others skilled in the art to which it appertains to make and use the same.

This invention relates to adjustments of the drill spindle carrying journals adjustably connected at the ends of arms in multiple spindle drills. It is a primary object and purpose of my invention to provide a simple yet efficient construction for readily loosening or tightening a drill spindle journal 15 with respect to the arm on which it is mounted. Arms of this character carrying journals usually require that the journal be connected to the arm at two spaced apart points, one above the other, the upper connection being hard to reach and almost inaccessible after the arm is attached to the supporting member of a drilling machine. The lower means of connection is readily accessible and my invention is directed to a 20 novel means for loosening or tightening the drill spindle journal against the arm through the operation only of the lower freely accessible connecting means used in attaching said journal to the arm.

35 The construction which I have used to embody the invention is shown in the accompanying drawings, in which:

Figure 1 is a partial plan view and section, the section being taken substantially on 40 the line 1—1 of Fig. 2, of an arm equipped with my invention.

Fig. 2 is a longitudinal section taken through the arm and attached journal member, the means of connection being shown in 45 side elevation.

Fig. 3 is a fragmentary section taken substantially on the line 3—3 of Fig. 2.

Fig. 4 is a view similar to Fig. 3 but showing the parts in different relation to 50 illustrate the method of assembly.

Fig. 5 is a partial plan view and section similar to Fig. 1, the section being taken substantially on the line 5—5 of Fig. 6; and

Fig. 6 is a longitudinal section similar to 55 Fig. 2, illustrating a slightly different means

of connecting the journal to the arm, both constructions, however, working on the same principle.

Fig. 7 is a partial plan section of a further modification, the section being taken 60 on line 7—7, Fig. 8.

Fig. 8 is a longitudinal section of the modification shown in Fig. 7 taken through the arm and attached journal member.

Fig. 9 is a partial plan section of still a 65 further modification.

Fig. 10 is a longitudinal section of the modification shown in Fig. 9, the attaching means being shown in elevation.

Like reference characters refer to like 70 parts in the different views of the drawing.

The arm 1 may be of any suitable form of construction, a journal carrying member 2 being located at one end thereof and formed with a journal 3 in which a vertical spindle 75 4 is rotatably mounted, the lower end thereof being equipped with any suitable drill holding socket 5. The end of the arm 1 has a wide and shallow slot 6 therein, preferably, and the journal member 2 is 80 formed with a suitable projecting tongue 7 to fit this slot 6 and hold the journal member against any tendency to move sidewise or twist with respect to the arm.

A vertical opening 8 is bored downwardly 85 through the member 2 back of the spindle 4 into which a cylindrical rod 9 may be entered from above. At its upper end rod 9 is machined to leave a sector projection 10 which is located at one side of the axis of 90 the rod. The other end has a similar sector projection 11 but is located at the opposite side of the axis of the rod. A stud 12 passes through a vertical slot 13 formed in the end of the rod 1 and into a horizontal opening 95 bored into the upper part of the journal member 2, this opening traversing the vertical opening 8. The end of the stud within the journal member is enlarged, has a transverse slot 14 cut therein on its under side 100 but leaving a downwardly extending projection or hook 15 which comes against a side of the projection 10 of the pin 9. Suitable securing and locking nuts 16 are threaded onto the end of the stud 12 which 105 passes through the arm, a washer 17 being located between one of the nuts and the adjacent portion of the arm as shown. The formation of the sector projection 10 is such that on tightening the nuts there is a tend-

ency to turn the pin 9 (referring to Fig 1) in a counter-clockwise direction.

A second and lower stud 18 passes through a lower vertical slot 13^a made in a downward extension 1^a to the end of the arm 1 and is located in a second horizontal opening bored into the journal member 2 so as to meet the lower end of the vertical opening 8. This stud 18 is similar to stud 12 except that the slot 19 is cut in its upper side to receive the lower sector projection 11 of the pin 9 and has a hook 20 to bear against a side of said projection 11 as shown. At its free end the stud 18 receives a nut 21 and a washer 22 is interposed between the nut and the adjacent portion of the arm 1. Tightening this nut has a tendency to draw the stud and turn the pin 9 in a clockwise direction or opposite to the movement which is imparted by tightening the nuts on the stud 12.

It is evident that on tightening the nut 21 and thus giving a clockwise direction of turning movement to the rod 9, there is a tendency to draw the stud 12 into the journal member so that if nut 21 alone is tightened so as to bind the lower portion of the journal member against the arm the effect is to simultaneously draw the upper portion 30 of the journal member against the arm with equal force. Similarly loosening the nut 21 will free the lower portion of the journal member and simultaneously free the upper portion thereof. When thus freed the journal member may be moved to different positions with respect to the arm within the limitations prescribed by the length of slots 13 and 13^a.

The hook portion at 20 is of slightly different form than that at 15 for the upper stud so as to permit the assembly of the parts. In assembling, the rod 9 is placed in the opening 8 and allowed to drop to the bottom thereof after which the stud 12 is inserted and the journal member inverted whereupon the pin 9 drops back so that its sector projection 10 enters the slot 14. The stud 18 is turned to the position shown in Fig. 4 and inserted into the journal member after which it is turned through a quarter of a circumference to its operative position shown in Fig. 3. This permits a quick and ready assembly of parts of the device used to bind the journal member against the arm.

In Figs. 5 and 6 a modification in structure is shown. The rod 9^a is modified in that the projections 10 and 11 do not appear but each end of the rod has a plurality 60 of pinion teeth 23 cut around it, while the studs 12^a and 18^a are each formed with an off-set rack 24 to engage the pinions thus made, the racks of the two studs engaging with the pinions at opposite sides of the rod 9^a. The effect, so far as turning the rod

9^a is concerned and simultaneously tightening or loosening both studs with the operation of the nut 21 only on the lower stud is the same as in the construction previously described.

In Figs. 7 and 8, a still further modification is shown. The vertical opening 8^a in the journal member 2 is made from the under side thereof and the rod 9^b located therein is of substantially triangular cross section and adapted to turn about one of the apexes of the triangle at one side of the opening as indicated at 25, showing that the rod does not need to turn about a central longitudinal vertical axis. The projections 10^a and 11^a at the upper and lower ends of the rod 9^b are also substantially triangular in cross section and so located that the hooked portions 15 and 20 bear against opposite apexes of the triangle so that when either stud is tightened or loosened the effect is to tighten or loosen the other stud simultaneously and in an equal amount.

In the constructions previously described, the rods 9, 9^a and 9^b have been shown as carried by the journal member 2. It is quite as feasible and practical to place the same on the arm as shown in Figs. 9 and 10. An opening to receive the rod 9^c is made in the end of the arm 1 which in this case does not have the slots 13 and 13^a therein. The projections 10^b and 11^b at the upper and lower ends of the rod are similar to projections 10 and 11 of the first construction, being reversed in position on the rod. The studs 26 have heads 27 which are received in a T-slot 28 made vertically in the journal member 2. A bushing 29 is placed around each stud to bear against the projections 10^b and 11^b, the nuts 16 and 21 bearing against the opposite ends of the bushings. The operation is the same and the effect thereof is the same as with the other construction described so far as tightening and loosening the journal member for adjustment is concerned.

Various other differently constructed embodiments of my invention will occur to others skilled in the art and I, accordingly, consider that my invention comprises all modifications of structure falling within the scope of the appended claims which define the invention and is not limited to the specific constructions shown and described.

I claim:

1. In a device of the character described, an arm, a journal member mounted at one end of the arm, said journal member having a vertical opening therein, a rod located in said opening, studs, one at each end of the rod projecting from the journal member through the arm, interengaging means between the ends of the rod and said studs for turning the rod about its vertical axis and simultaneously moving one stud as the other stud is moved but in an opposite direction,

- and nuts on the free ends of the studs for binding the journal member to the arm, substantially as and for the purposes described.
2. Connecting means for attaching a drill spindle journal member to the end of an arm, comprising a rod loosely mounted within the journal member, means located at each end of the rod and passing through and engaging with the end of the arm, interengaging means between each of said first mentioned means and the ends of the rods for turning the rod about its longitudinal axis on movement of either of said means, said turning movements imparted to the rod being opposite with the two means, substantially as described.
3. In a construction of the character described, an arm, a drill spindle journal member located against one end of the arm, a rod adapted to turn about a vertical axis mounted on the journal member, and means connected with each end of the rod for securing the journal member to the arm, each of said means being movable lengthwise and operable to turn the rod about its vertical axis, and said means at one end of the rod turning the rod in a direction opposite to that imparted by the means at the other end of the rod, substantially as and for the purposes described.
4. In a construction of the character described, an arm, a drill spindle journal member located against the one end of the arm, a rod mounted loosely on the arm and adapted to turn about its longitudinal axis, a stud located at each end of the rod, said studs passing through the end of the arm and receiving nuts, and means connecting each stud with the adjacent end of the rod whereby movement of either stud longitudinally will turn the rod about its axis and move the other stud longitudinally but in a direction opposite to the movement of the first stud, substantially as described.
5. In a device of the character described, an arm, a drill spindle journal member located against the end of the arm, upper and lower studs located partly in the journal member and extending therefrom and through slots in the end of the arm, nuts threaded onto the ends of the studs, a rod disposed between the opposite ends of the studs, and means connecting the ends of the rod with said upper and lower studs whereby tightening the nut on one of the studs, thereby moving it longitudinally, serves to rotate the rod and draw the other stud in the opposite direction so as to bind the nuts carried thereby against the arm simultaneously and with equal force, substantially as and for the purposes described.
6. In a construction of the character described, an arm, a drill spindle journal member located against the end of the arm, said journal member having a vertical opening 65 therein, a rod located loosely in said vertical opening and provided at each end with a sector-shaped projection, said projections at opposite ends of the rod being located at opposite sides of the axis of the rod, two 70 studs provided with hooked ends located in horizontal openings made in the journal member one at each end of said rod, said hooked ends engaging with the projections on the rod and said studs passing through 75 vertical slots in the end of the arm, and nuts threaded onto the ends of the studs back of said end of the arm, substantially as and for the purposes described.
7. In a device of the character described, 80 an arm, a drill spindle journal member located against one end of the arm, a rod mounted in the journal member and adapted to turn about its longitudinal axis, two separate means connected with the rod and 85 adapted to detachably and adjustably connect the journal member to the end of the arm, and interengaging means between each of said two means and the rod for tightening or loosening one of said means simultaneously with the tightening or loosening of the other operable through a turning of the rod about its longitudinal axis, substantially 90 as and for the purposes described.
8. In a construction of the character described, 95 an arm, a drill spindle journal member located against one end of the arm, a rod loosely mounted on one of said members and adapted to turn about an axis parallel 100 with the length of the rod, and means associated with each end of the rod for connecting the arm and journal member together, each of said means being movable lengthwise and operatively connected with the rod so as to turn the rod about said axis, 105 one of said means acting to turn the rod in one direction and the other in the opposite direction, substantially as and for the purposes set forth.
9. In a construction of the character described, 110 an arm, a drill spindle journal member located against one end of the arm, a rod loosely mounted on one of said members and positioned vertically thereon and adapted to turn about a vertical axis parallel 115 with the length of the rod, and upper and lower means for connecting the arm and journal member together, each of said means having operative connections with the rod adjacent its upper and lower ends, said means each being movable longitudinally and operating to turn the rod about said axis, one of said means acting to turn the rod in one direction and the other in the opposite direction, substantially as and for 120 the purposes described.
- In testimony whereof I affix my signature.
EDGAR W. CLEVELAND.
